**METHOD OF COMPOSING TYPE AND TYPE
AND BACKING ELEMENT THEREFOR**

John A. Willett, Boston, Mass., assignor to Davidson Corporation, Brooklyn, N. Y., a corporation of Illinois

Application December 17, 1953, Serial No. 398,824

1 Claim. (Cl. 96—43)

This invention relates to methods of composing type and to improvements in type elements and to sheets or base elements on which the type elements are assembled during type composing. It relates more particularly to improved kinds of base sheet and type elements which can be assembled on the base sheet to compose copy in an inexpensive and quick manner.

It has been proposed heretofore to form letters, words, symbols and the like necessary for type composition on transparent or thin flexible backings. Such symbols, letters, logotypes and the like have been provided with a sticky substance on the backs thereof so that they can be stuck to a supporting plate such as a piece of glass or a piece of transparent plastic white or black paper or the like to form a composition that may be photographed or from which a print may be made on photographic film to enable a printing plate to be made therefrom. Type elements having sticky backs thereon are not very practical. The sticky material or adhesive on the back thereof causes them to bond so tightly to the supporting backing that they cannot be shifted readily if they should be improperly positioned, as is often the case. Moreover, they must have a protective covering over the adhesive as otherwise they would stick together and be difficult to separate and to apply to the backing sheet. The difficulty of removing the covering while composing slows the operation excessively.

Difficulty has been encountered heretofore in providing type elements of the kind described from which sharp, clear printing plates can be produced. The prior type elements are normally produced by a printing with ink. They have not been satisfactory because they are not sufficiently opaque and sufficiently free of imperfections such as scratches, bubbles, pinholes and the like, to enable clear, sharp copies to be made thereof.

The difficulties and disadvantages inherent in the prior articles have been overcome by the present invention by providing type elements, logotypes, symbols and the like which are clear, sharp and sufficiently transparent and opaque to enable clear, sharp copies thereof to be made. In accordance with the invention, the type elements preferably are made photographically so that the type elements are photographically sharp images. Typical type elements may consist of a transparent backing having on one side a photographic emulsion in which the image is formed and on the opposite side a stress coating to prevent bending of the flexible support and also to promote improved adhesion to the supporting base on which the type elements are assembled. The type elements in accordance with the invention are free of tacky or adhesive material so there is no danger of their sticking together, no protective backing is required thereon and because of their lack of stickiness, they can be used and reused as required.

The backing sheet on which the types, logotypes, symbols and the like are composed in accordance with the present invention is of a transparent and stiff nature and may be formed of any one of the series of materials such

as glass, transparent plastics and the like. The backing is provided with a surface coating of a peculiar and most advantageous type which greatly facilitates the composition or assembly of the type thereon. The backing is provided preferably with a thin coating of a material which is not sticky to the touch but which will adhere lightly to articles which are pressed against it. The adhesive property is such that the article can be detached readily from the adhesive without the latter clinging to the article. A preferred type of adhesive which is highly satisfactory in practice is a microcrystalline wax of slightly tacky nature having a melting point in the vicinity of about 140° to 160° F. This wax is sufficiently tacky to hold the type elements in position when they are pressed against it, but they are not held so firmly that they cannot be detached and shifted to another position. The film of wax differs from the pressure sensitive adhesives which hold the type elements so tenaciously that they cannot be removed therefrom or shifted if improperly located or positioned. Moreover, the wax has little tendency to collect dirt thereon and in fact, may be readily cleaned if dust or dirt does settle thereon. Moreover, the wax film can be reconstituted merely by warming the plate and thereby melting and restoring the wax as a thin film on the backing.

With type characters or elements and a backing sheet of the type described the types can be assembled in a desired relation on the surface of the backing sheet where they are retained sufficiently tenaciously to enable a print to be made thereof on photosensitive paper or film. From this negative, a positive can be produced and from the positive, in turn, can be made gravure type of plate by a suitable printing operation. Inasmuch as the method does away with the production of complicated type setups and the materials involved are inexpensive, it is possible to produce a printing plate for only a fraction of the price normally required for production of a conventional printing plate.

The process has the advantages that it may be used for printing newspapers, flyers, bulletins and the like without involving complicated apparatus or such expensive operations as to render the method unfeasible.

For a better understanding of the present invention, reference may be had to the accompanying drawing in which:

Fig. 1 is a plan view of a typical backing sheet for reception of type characters, symbols and the like to be composed thereon;

Fig. 2 is a view in section through a portion of the backing plate taken on line 2—2 of Fig. 1 and shown somewhat enlarged;

Fig. 3 is a view of a character embodying the invention;

Fig. 4 is a view in section taken on line 4—4 of Fig. 3 and shown greatly enlarged;

Fig. 5 is a plan view of the front of a board used for composing type illustrating the backing sheet thereon and types in position on the backing sheet;

Fig. 6 is a plan view of the back of the composing board; and

Fig. 7 is a sectional view of the backing sheet with type thereon and a filter and diffusing sheet assembled therewith in contact with a sheet of photosensitive paper in the process of making a paper or film negative from the assembled article.

The invention will be described with reference to typical articles and procedures involved in the composition of type on a backing sheet embodying the present invention.

Referring to Figs. 1 and 2, the backing sheet on which the type is to be composed or read may consist of a sheet 10 of transparent plastic, glass or the like of suitable dimensions. Sheet 10 preferably is formed of a

transparent, yellow tinted plastic such as "Lucite" or "Plexiglas" which is about one-sixteenth to one-eighth inch in thickness. The sheet should be sufficiently durable to enable it to be handled without breakage. The sheet 10 is provided with a surface coating 11 of an adhesive material which is used to secure the type elements described hereinafter, to the surface of the sheet. The preferred tacky adhesive for use on a sheet is a micro-crystalline wax having a melting point in the vicinity of 140° to 160° F. A wax of the type described has been found to be highly suitable for the surface coating because it has a slightly tacky character which enables it to adhere to type characters of the kind disclosed herein. A wax suitable for the purpose is manufactured by the Warwick Wax Company Inc., of Chanute, Kansas, and known as Warco Wax 150, yellow. The wax melts between about 145° and 150° F. Other similar waxes can be used. Other petroleum or paraffin waxes which have been plasticized or otherwise treated to render them slightly tacky may be used equally well. Other pressure sensitive adhesives which are treated to reduce their stickiness or manufactured to provide only a slight surface tackiness may also be used.

The wax coating 11 is applied to the slightly preheated base 10 with the standard type roller coating equipment or in any other desired way and is allowed to dry in air without calendaring or polishing. When the wax has hardened, it has a slightly misty or matte surface which, nevertheless, is highly translucent or substantially transparent. The wax coating 11 is of such character that dust or dirt can be blown off of it quite readily and if the dirt should be embedded by pressure in the wax, it can be picked off with a knife or other tool and the marred surface of the wax restored by warming the plate slightly to remelt the wax.

The type elements used for composing on the base sheet described above are novel in structure. The individual type elements 14, for example, are made in suitably related sizes. For example, the letters of a font of type are proportioned in such manner that when they are assembled edge-to-edge, their spacing, width and height are properly related. The type characters are formed, preferably, on a photographic film, the base of which may consist of a thin, relatively stiff sheet of transparent material 15. A typical base material is stiff, transparent vinyl sheeting about .01 to .0125 inch in thickness. The film has on one surface 16 a photographic emulsion preferably of the high contrast, contact chloride emulsion type and on its back surface a stress coating 17 to prevent curling of the film due to the presence of the photographic emulsion thereon. The stress coating is formed of gelatin or the like and may contain an anti-halation dye. It is characterized by a slightly roughened or matte surface for a purpose to be described.

The photographic emulsion on the front side of the sheet 15 is exposed in any suitable way and is developed and fixed to reproduce photographically the particular character or symbol thereon which is desired. The individual characters can be made in strips or sheets by a "step and repeat" or other photographic operation enabling them to be made in large quantities. The photographically produced characters on the sheets can be made much sharper than can ordinary ink printed characters and the photographic characters are highly opaque and are free from pin holes or specks which mar the overall opacity of characters printed with ink. The provision of characters which have a photographic emulsion on one side and a slightly matte or roughened stress coating on the back side is advantageous in that it has been found that a smooth photographic emulsion does not stick readily to the wax coating 11 on the backing sheet 10 while the matte surface of the stress coating sticks quite firmly. The difference in the surfaces of the characters makes it difficult to assemble or compose the characters in an upside down or backwards position. Thus, the

characters will stick relatively tightly when their roughened surfaces are pressed against the wax coating but do not stick readily when the photographic emulsion is pressed against the wax coating 11. Moreover, the type characters may be provided with tactile indicators such as nicks or notched corners 18 at their upper right-hand corners, so that they will not be composed upside down or upside down and backwards. This might occur with letters such as d, b, p, q and g. These letters might be used improperly and would destroy alignment in the composition if not provided with some indicating means in addition to the smooth and matte surfaces of the characters.

In order to facilitate the composing of the types on the backing sheet, I have provided a composing board which consists of a board backing 20 of any suitable size having a pair of register or locating pins 21, 22 for engagement in corresponding openings 23, 24 in the top of the base sheet 10. The board has a crossbar 25 extending across its back which is connected at its opposite ends to channel members 26 and 27 sliding on the side edges of the board 20. The back of the board is also provided with pulleys 30, 31, 32 and 33 at its corners over which are passed cables 35 and 36 connected to the opposite ends of the crossbar so that it can be moved up and down only parallel to the top and bottom edges of the board.

At the front of the board is a scale or straight edge 37 which may be detachably or movably connected to the channel members 26 and 27. As illustrated, it is provided with openings for receiving the guide pins 38 and 39 extending up from the channels to enable the straight edge to be lifted off the channels and replaced accurately thereon.

The straight edge 37 may be provided with a pica scale at its upper edge and an inch scale at its lower edge and the board may also be provided with a vertical pica scale along its edge.

In use, the base sheet 10 is placed on the composing board 20 with the register pins 21, 22 engaging in the openings 23, 24 in the base sheet 10. The types 14, 14 etc. are then assembled in the desired relation along the scale so they are maintained in a straight line. Due to the releasable adhesive nature of the wax, any adjustment of the types that is required may be accomplished by lifting and placing the type characters before finally pressing them tightly against the coating 11. Even then, they can be readily lifted, if further adjustment is found to be necessary.

When the composition is completed, the backing sheet 10 with the types 14 assembled thereon can be transferred to a vacuum printing frame where it is covered with a filtering and diffusing sheet 40 of thin colored plastic, for example, yellow or amber cellophane or vinyl sheeting which conforms itself to the type characters and the front of the sheet. A sheet of photosensitive paper 41 or film is then placed in contact with the film and the whole assembly is placed in a vacuum frame where the exposure is made through the types 14 and backing sheet 10 and the filter sheet 40 onto the photosensitive paper 41. The resulting negative may then be developed and fixed. A paper negative is produced when photographic paper is used in the process. A transparent negative may be produced, if desired, by using photographic film instead of paper. The diffusing sheet 40 is used to mask out and diffuse pin holes, the cut edges of the type elements or other surface imperfections like dust specks on the subject. Evidently the spacing afforded by the sheet 40 is such as to diffuse the light and conceal the surface imperfections which otherwise would show up in the final copy. Nevertheless, it has been found that the edges of the type characters are sharp and clear.

The negative 41 produced above may be used for the production of a positive and the positive may be used

to produce a printing plate of a desired kind by known methods.

In the production of a printing plate, as described above, the principal expense involved is in the photo-sensitive paper and in the plate itself. The type elements involved in the composition may be reused repeatedly as can the base sheet. Thus, the initial expense for these items is not repeated in the production of each plate and in fact many different type compositions can be produced from the original kit.

The type elements may be retained in any sort of a type holding box, for example, a simple box having upright partitions therein and having a coating of wax like that used on the base plate 10. The type elements may be stuck to the wax coating in a more or less upright position. The type box enables the type elements to be picked off rapidly and transferred to the base sheet as may be required. Moreover, they can be restored to the type box and stuck to the partitions therein with a minimum of effort.

From the preceding description, it will be apparent that I have provided a method of composing type, apparatus for accomplishing the same and base sheets and type elements which coact in a new manner which in themselves have characteristics not known heretofore in this art. They overcome almost completely the difficulties encountered heretofore in providing types of an inexpensive yet sharp and clear character that could be stuck readily to a base sheet adjusted on it and can be reused repeatedly.

While reference has been made to the elements 14 as having types or type characters thereon, it will be understood that they may be printed with other symbols such as chemical symbols, electrical symbols and the like which may be arranged to indicate chemical compounds, electrical circuits or even schematic showings of flow sheets and the like in chemical and other industries, as may be required. In each case, it will be understood that symbols or characters will be of appropriate size so as to fit together and be related with other elements with which they are used.

It will be understood that in some instances, it may be desirable to provide reversed types so that instead of having opaque characters on a clear or transparent background, the background may be made actinically opaque while the letters are transparent to thereby produce different effects as may be required.

It will be understood that many different fonts of type

may be produced for achieving different effects. Thus, the fonts may be made in several different sizes of capitals and in various sizes and forms of italics or script. Entire words (logotypes) may be formed, for example, for use in making flyers or bulletins for use for advertising in grocery stores, drug stores and the like as the case may be. Accordingly, the forms of the invention disclosed herein should be considered as illustrative of the invention and the claim therefore should not be considered as limited thereby except in so far as specified therein.

I claim:

A method of composing type and making prints therefrom, comprising assembling a plurality of lines of type elements on a transparent base sheet, said sheet having a continuous substantially transparent film of a slightly tacky microcrystalline wax substantially covering one of its surfaces, each type element comprising a piece of thin, transparent material having a surface coated with a smooth, photographic emulsion non-adherent to said wax, said emulsion containing a developed and fixed photographic print of an opaque type character, said type element having an opposite surface with a coating thereon for preventing curling of the type element, said coating being non-adhesive but roughened to render it adherent to said wax film when pressed against the wax film, placing over the assembled lines of type elements a transparent diffusing sheet, placing in contact with said diffusing sheet a photo-sensitive member and exposing the latter to light through said base sheet, the type elements assembled on the base sheet and the diffusing sheet to make a print therefrom.
